UNITED STATES PATENT OFFICE.

JENNIE B. PARKER, OF ALBION, MICHIGAN.

HIGH-CHAIR TRAY.

1,254,155.

Specification of Letters Patent. Patented Jan. 22, 1918.

Application filed May 28, 1917. Serial No. 171,506.

To all whom it may concern:

Be it known that I, JENNIE B. PARKER, a citizen of the United States, residing at Albion, in the county of Calhoun and State 5 of Michigan, have invented certain new and useful Improvements in High-Chair Trays; and I do declare the following to be a full, clear, and exact description of the invention, such as will enable others skilled in the art 10 to which it appertains to make and use the same.

My invention relates to high chair trays and its object is to provide a tray of this character in which all parts are readily accessible for thorough cleansing thereof and 15 in which means are provided to retain a supplemental tray thereon which supplemental tray may be removed when desired.

A further object of the invention is to provide 20 a high chair tray provided with side pieces adapted to act as flanges to receive the supplemental tray thereunder and which side pieces are spaced above the bottom of the tray by means of uprights so that when the 25 supplemental tray is removed no crevices or grooves will be left in the tray proper in which food or dirt may accumulate.

With these and other general objects in view which will appear from the description, 30 my invention resides in the novel construction, combination and arrangement of parts as will be fully hereinafter described and claimed when taken in connection with the accompanying drawing which forms a part 35 of this application and in which:

Figure 1 is a side elevation of a chair showing my improved tray as applied;

Fig. 2 is a side elevation of the tray;

Fig. 3 is a top plan view of the same;

Fig. 4 is a longitudinal sectional view on the line 4—4 of Fig. 3;

Fig. 5 is a transverse sectional view taken on the line 5—5 of Fig. 3.

In detail my invention comprises a flat 45 substantially rectangular tray having a base 1 provided with an outer guard wall 2 extending upright from the outer edge thereof and having parallel spaced upright spindles 3 disposed along its side edges spaced 50 slightly inward therefrom, which spindles are adapted to act as supports for relatively wide flat side pieces 4 disposed in parallel relation to the base 1 and spaced thereabove. These side pieces are secured at 55 one end to the outer guard wall 2 and are

rounded at their inner ends and extend inward of the tray.

This tray in the construction described may be used as a unit and may be kept clean at all times as the side pieces 4 are maintained in spaced relation above the bottom of the tray a sufficient distance so that no crumbs of food or dirt may lodge between the pieces and base and owing to the spaced arrangement of the spindles 3 openwork 60 sides are provided which add materially to the efficient cleansing of the tray as it will be practically impossible for any dirt to become lodged at the sides of the tray. With the majority of trays of this character it 65 is customary to use a supplemental tray for holding food and the like and accordingly I employ a supplemental tray 5 which is suitably formed of white enamel as it is most readily kept clean and which is provided 70 with the usual upstanding side edges 6 and beveled end edges 7. At its inner end the supplemental tray is provided with a handle 8 so that when being applied the side edges 6 are inserted beneath the inwardly extending 75 portions of the side pieces 4 with the spindles 3 acting as guides for the sides of the tray and the tray 5 slid over the base until contacting with the outer guard wall 2. The supplemental tray will thus be held 80 effectually on the main tray as the inwardly extending side pieces will prevent vertical displacement of the tray and inward movement of the tray is prevented by the body 85 of the infant in the chair. The tray is removed by being slid inwardly of the chair 90 and from beneath the side pieces 4.

I desire to emphasize strongly these essential features of my invention comprising the vertically spaced side pieces 4 supported on 95 the parallel spaced spindles 3 as this construction which has been described provides an openwork side for the main tray as well as a flange for receiving and guiding a supplemental tray thereon, which is at all times 100 readily cleansed and in which it is practically impossible for any dirt to become lodged and thereby rendering the tray unsanitary.

While I have described and illustrated in 105 the accompanying drawing certain details and materials entering into the construction and operation of my improved tray, I desire to be understood that I do not intend to limit myself specifically to these, but that 110

any changes may be made in the same that will fall within the scope of the invention as claimed.

I claim:

5. 1. A tray for high chairs comprising a flat substantially rectangular base, a raised guard wall thereon, side pieces on said tray spaced upright to support said side pieces in vertically spaced relation above the bottom of the tray, a supplemental tray to be slidably engaged on said base beneath the side pieces and guided between said uprights.
10. 2. A tray for high chairs comprising a flat substantially rectangular base, an upright guard wall at the outer edge thereof, parallel spaced spindles extending upright along the side edges of said base, side pieces

supported on said spindles in vertical spaced relation above said base and extending inwardly from the sides thereof, said pieces being adapted to receive the side edges of a supplemental tray thereunder when the same is slidably engaged with said base, the spindle members serving to guide said supplemental tray when being applied and providing open sides for said tray for efficient cleansing.

In testimony whereof I have hereunto set my hand in the presence of two subscribing witnesses.

JENNIE B. PARKER.
